No. 36,822.

Patented February 23, 1904.

UNITED STATES PATENT OFFICE.

FREDERICK A. ARBENZ, OF WEST HOBOKEN, NEW JERSEY.

DESIGN FOR FABRIC.

SPECIFICATION forming part of Design No. 36,822, dated February 23, 1904.

Application filed June 8, 1903. Serial No. 160,667. Term of patent 14 years.

To all whom it may concern:

Be it known that I, FREDERICK A. ARBENZ, a citizen of the United States, residing in West Hoboken, in the county of Hudson and State of New Jersey, have invented a new, original, and ornamental Design for Fabrics, of which the following is a specification, reference being had to the accompanying drawing, forming a part thereof.

The figure of the drawing is a plan view of 10 a piece of fabric, showing my new design.

I claim as my invention—
The ornamental design for a fabric, as shown.

FREDERICK A. ARBENZ.
